Primary Examiner — Natasha Vujcic*Assistant Examiner* — Gilbert B Ford(74) *Attorney, Agent, or Firm* — BakerHostetler(57) **CLAIM**

We claim, the ornamental design for a liquid transfer device, as shown and described.

DESCRIPTION

FIG. 1 is a perspective view of a liquid transfer device; and, FIG. 2 is a cross-sectional view thereof.

The dashed broken lines in the figures show portions of the liquid transfer device that form no part of the claimed design.

1 Claim, 2 Drawing Sheets# US D954,253 S
